UNITED STATES PATENT OFFICE.

JAMES K. MCKELVEY, OF WARNOCK, OHIO.

CLUTCH.

1,017,577.

Specification of Letters Patent. Patented Feb. 13, 1912.

Application filed May 9, 1911. Serial No. 625,980.

To all whom it may concern:

Be it known that I, JAMES K. MCKELVEY, a citizen of the United States, residing at Warnock, in the county of Belmont and 5 State of Ohio, have invented new and useful Improvements in Clutches, of which the following is a specification.

This invention relates to improvements in clutch mechanism, the primary object of 10 the invention being to provide a combined frictional and positive clutch mechanism which is of a simple construction, which is strong, comparatively cheap to manufacture, and which will perform its functions 15 with ease and with accuracy.

With the above objects in view, and others which will appear as the nature of the improvement progresses, the invention resides in the novel construction and combination 20 of parts hereinafter fully described and claimed.

In the drawings, accompanying this specification, there has been illustrated a simple and approved embodiment of the invention, 25 it being understood, however, that the showing therein is merely illustrative and that changes in the minor details of construction which fall within the scope of the appended claim may be made, if desired.

30 In the drawings,—Figure 1 is a front elevation of the clutch mechanism embodying my invention. Fig. 2 is a side elevation of the same. Fig. 3 is a central vertical longitudinal sectional view of the same. Fig. 4 is a detail perspective view of the sleeve 35 employed with my improvement. Fig. 5 is a front elevation of the rear wheel. Fig. 6 is a perspective view of the sliding collar. Fig. 7 is a similar view of the shifting member.

40 In the accompanying drawings, the numeral 1 designates a shaft to which is attached a fly wheel 2. Secured to the inner face of the fly wheel 2 is an annular clutch band 3. Mounted upon the shaft 1 is a sleeve 4. This sleeve is provided with a plurality of longitudinally extending ribs or projections 5, the purpose of which will presently be set forth.

45 The numeral 6 designates the sliding collar which has its bore formed with longitudinally extending depressed portions 7, the latter corresponding in number with the ribs or beads 5 of the sleeve 4, and with 55 which they are adapted to engage.

The collar 6 is centrally provided with an

annular enlargement 8, the same adapted to be engaged by the walls provided upon slotted shoes 9, which are pivotally connected with the opposite ends of a yoke 10 provided upon a shifting member 11.

The device is primarily adapted to be used in connection with a traction engine, but is, of course, susceptible for use in other connections, and the shifting member 10 is 60 pivotally connected as at 12 to any desired portion of the frame of the engine. The extremity of the arm 11 is preferably bifurcated to receive a pivoted member 13 which may be secured to a lever or the like within 65 the cab of the engine. The sliding collar 6 is provided with a plurality of pockets 14, and arranged within these pockets are the pin members 15. These pin members 15 are partially projected from the pockets 70 through the medium of helical springs 16, and the said pins align with a plurality of openings 17 formed in the face of the fly wheel 2. The inner face of the collar 6 is further provided with a plurality of ears 18. 75 These ears are adapted to receive pivoted rods 19. Each of the rod members comprise a pair of sections having their adjacent ends threaded as at 20, and connected with the said threads are the turn buckles 21, by 80 which means the rod members may be adjusted.

The numeral 22 designates a spider which is also connected with the sleeve 4. The spider 22 comprises a central or connecting 90 portion and a plurality of regulating arms, preferably three in number, as illustrated in Fig. 1 of the drawings, and these arms are designated by the numerals 23.

The numerals 24 designate the brake shoes 95 of the device. Each of these brake shoes is provided with an off-set arm 25 which is pivotally connected as at 26 with the arms 23 of the spider 22. Connecting the off-set members 25 with the arms 23 of the spider 100 are the helical springs 27, the latter adapted to exert an inward pressure to retain the shoes 24 away from the band 3. The arms 25 are each pivotally connected with the upper member of each of the rods 19, as at 105 28, and from the above description, taken in connection with the drawings, it will be noted that when the collar 6, through the medium of the shifting member is slid upon the sleeve 4 toward the fly wheel 2, the rods 110 19 will serve to force the shoes 24 against the band 5, and a further movement of the

said collar will cause the pins 15 to engage within the recesses or openings 17 of the fly wheel, thus positively clutching the said fly wheel. By providing the pins with the 5 springs the said pins, while forced within their pockets in passing over the flattened outer face of the fly wheel, will be readily forced within the opening or recesses 17 of the said wheel, thus the device may be operated without danger of breaking the pins. 10 It will, of course, be further understood that the rods 19 are arranged at an angle to the fly wheel.

By reference to the figures of the drawing, it will be noted that the cog wheel 3' has its bore formed with a plurality of recesses or depressions 30. These depressions do not extend entirely through the bore, so that a portion of the cog wheel may 15 be mounted upon the outer extremity of the beaded or ribbed sleeve 5, while the remaining portion of the bore of the sleeve engages the shaft 1.

It will be apparent that when the shifting member is swung upon its pivot 12, the shoes 9 thereof, engaging with the annular enlargement provided upon the collar 6 will cause the said collar to travel upon the sleeve 4 toward the wheel 2, thus swinging the 20 rods 19 upon their pivots to cause the brake shoes 24 to likewise swing upon their pivots and against the pressure of their springs, so as to force the said brake shoes tightly 25

into engagement with the annular band 3 carried by the wheel 2.

Having thus fully described the said invention, what I claim is:—

The combination with a fly wheel having a brake band and mounted upon an axle, of a ribbed sleeve loosely positioned upon the axle, a sliding collar having its bore provided with a plurality of recesses adapted to engage with the ribs of the sleeve, a spider mounted upon the ribbed sleeve, a plurality of brake shoes having angular 40 arms pivotally connected with the arms of the spider, resilient means for normally retaining the brake shoes out of contact with the brake band, angularly arranged adjustable rods connecting each of the brake shoes 45 with the collar, the said collar being provided with a plurality of openings, springs within the openings, pins within the openings and adapted to be contacted and partly ejected from the openings by the springs, 50 and the fly wheel being provided with a plurality of openings corresponding in number and arranged in register with the pins, and means for sliding the collar.

In testimony whereof I affix my signature 55 in presence of two witnesses.

JAMES K. McKELVEY.
